UNITED STATES PATENT OFFICE

2,657,454

STRAND INSERTION

Daniel Duhurst Huyett, Wilmington, Del., assignor to Atlas Powder Company, Wilmington, Del., a corporation of Delaware

Application December 24, 1947, Serial No. 793,747

10 Claims. (Cl. 29—148)

1

This application relates to the working of resilient substances.

An object of the invention is the provision of methods and apparatus for inserting a strand material into a resilient substance.

Another object of the invention is the provision of methods and apparatus for the insertion of wire into a resilient substance.

A further object of the invention is the provision of methods and apparatus for the insertion of a leg wire into a resilient plug for an electric detonator.

Other objects of the invention will be apparent from the following description:

Units made up of strand material fixed in resilient substance find application in many industrial devices. Often it is desirable that the strand material and resilient substance be in water-proof relation. An example is an electric blasting cap sealed with a rubber plug through which leg wires are led.

By the present invention, methods and apparatus are provided whereby strand material may be inserted through a resilient substance in a manner such that the strand material is gripped tightly by the resilient substance.

According to the method of the present invention, a needle and a sleeve fitting around the needle are inserted through a resilient substance, the needle is removed from space encompassed by the resilient substance, strand material is inserted into the sleeve, and the sleeve is withdrawn from the resilient substance permitting it to shrink about and grip the strand material.

The invention also comprises an apparatus for performing this method in which a holding means is provided for the resilient substance, and a needle and a sleeve fitting therearound are coaxially provided in position to enter the resilient substance.

In one specific embodiment of the method of the invention, the needle and sleeve are respectively supported on opposite sides of the substance through which strand material is to be inserted. The resilient substance is first pierced through by the needle, and then the sleeve is slipped through the resilient substance over and around the needle. These operations produce an expanded hole in the resilient substance. The needle is then withdrawn from the sleeve; the strand material is inserted in the sleeve in place of the needle; and finally the sleeve is withdrawn from the resilient substance to shrink about and grip the strand material.

In another specific embodiment of the inven-

2

tion, the sleeve and needle are supported in axial alignment on the same side of the resilient substance. With the sleeve surrounding the needle, the resilient material is pierced by the needle following which it is further expanded by the sleeve. The needle is then retracted from the position of the sleeve encompassed by the resilient substance; the strand material is inserted into the sleeve; and finally the sleeve is withdrawn from the resilient substance.

In a further specific embodiment of the invention, the needle and sleeve are respectively supported in axial alignment on opposite sides of the resilient substance. The resilient substance is first pierced through by the needle. The sleeve is then passed over the point of the needle. Next the sleeve is passed through the resilient substance while the needle is simultaneously withdrawn therefrom. The needle is then withdrawn from the sleeve; a leg wire is inserted in the sleeve; and finally the sleeve is withdrawn from the resilient substance.

The invention will be further described by means of the drawings which illustrate the three specific embodiments mentioned above as applied to the insertion of two leg wires into a resilient rubber-like plug, and in which:

Figure 1 is a side elevation of one apparatus suitable for carrying out the invention;

Figure 2 is an end sectional view of portion 19 of the apparatus shown in Figure 1;

Figure 3 is an enlarged sectional view of portions 19 and 43 of the apparatus shown in Figure 1;

Figure 4 is a further enlarged sectional view of parts of the apparatus shown in Figure 3 in a different position of operation;

Figure 5 is a view similar to Figure 4 but showing the parts in a further position of operation;

Figure 6 is a view similar to Figure 4 showing another point in the operation of the apparatus;

Figure 7 is a view similar to Figure 4 showing a still further point in the operation of the apparatus;

Figure 8 is a side elevation partly in section of an electric blasting cap;

Figure 9 is a top view of an apparatus suitable for carrying out the invention in a modified manner;

Figure 10 is a side elevation, partly in section, of the apparatus shown in Figure 9;

Figure 11 is a sectional view of a portion of the apparatus shown in Figure 10 taken through line 11—11 on Figure 10;

Figure 12 is a side elevation partly in section

3

of an apparatus for carrying out the invention in another modified manner; and

Figure 13 is an enlarged view of a portion of the apparatus shown in Figure 12 in another position of operation.

The embodiment of the invention shown in Figures 1 through 8 will be described first. As shown in Figure 1, 14 is a standard secured to a support 15 by means of bolts 16 and 17. A lower portion of standard 14, designated at 19, contains a recess of a size to receive a resilient rubber-like plug 21 (see also Figures 2 and 3 where plug 21 is shown partly in section). Through the bottom of portion 19 is slidably mounted clevis 23, which is operated by handle 25 (Figure 1). Handle 25 is pivoted in bracket 21 on standard 14 by pin 29 and is pivoted in clevis 23 by pin 31. Clevis 23 is limited in its downward motion by pin 33.

At the top of standard 14 (Figure 1) is rotatably mounted pinion 35 actuated by handle 37 so as to drive rack bar 39 vertically. At the base of rack bar 39 is affixed a needle holder indicated generally at 43.

Referring now to Figure 3 wherein needle holder 43 and plug holding portion 19 are shown in more detail, clevis 23 fixedly supports two tubular sleeves 45 and 47. As clevis 23 is moved by handle 25, sleeves 45 and 47 slide respectively in tunnels 49 and 51.

Needle holder 43 is held in rack bar 39 by rod 41 and screw 42 (Figure 1). Rod 41 is enlarged below rack bar 39. At the top of the enlarged portion of rod 41 is mounted collar 53 fixed thereon by screw 55. Bearing against collar 53 is spring 57, which at its opposite end bears on guide member 59. Guide member 59 is held on rod 41 by pin 61 extending diametrically through rod 41, and is permitted limited longitudinal movement thereon by diametrically opposed slots 63 (one of which appears in Figure 1, and the other of which appears in Figure 3). Embedded in the bottom of rod 41 and extending through guide member 59 are two needles 65 and 67. It will be seen that the turning of handle 37 (Figure 1) and the resultant movement of rack bar 39 in a vertical direction moves needle holder 43 in a vertical direction.

The operation of the device will be described, particularly in connection with Figures 1, 3, 4, 5, 6, and 7, which show successive points of operation. With the apparatus in position shown in Figures 1 and 3, parts 19 and 43 are separated. Handle 37 is then turned so that needle holder 43 carrying needles 65 and 67 is brought down. Needles 65 and 67 pierce plug 21 and continue therethrough until they enter sleeves 45 and 47. (See Figure 4.) It is to be noted that guide member 59 is thereby pushed up (relative to the remaining parts of needle holder 43) against spring 57, but that guide member 59 protects needles 65 and 67 against bending stress as they enter plug 21.

Then, after the parts are in the position shown in Figure 4, lever 25 (Figure 1) is raised pushing clevis 23 upward so that it in turn pushes sleeves 45 and 47 around needles 65 and 67 and through rubber plug 21. (See Figure 5.) Handle 37 (Figure 1) is then turned so that needle holder 43 is retracted withdrawing needles 65 and 67 from sleeves 45 and 47, and needle holder 43 once again assumes the position shown in Figures 1 and 3. Then while sleeves 45 and 47 still extend through plug 21, insulated wires 69 and 71 are respectively inserted down into sleeves 45 and 47 as shown in Figure 6.

4

Lever 25 (Figure 1) is then pushed down carrying clevis 23 which in turn pulls sleeves 45 and 47 out of plugs 21. As sleeves 45 and 47 leave plug 21, it shrinks about and grips insulated wires 69 and 71 (see Figure 7). Plug 21, containing wires 69 and 71 embedded in it, may then be removed and, after insertion of a new plug 21, the apparatus is ready for another cycle of operation.

Plug 21 containing wires 69 and 71 may be advantageously used as a sealing plug for an electric blasting cap, as is shown in Figure 8. To make the blasting cap of Figure 8, shell 77 is charged with base charge explosive 79, primary detonating explosive 81, and initiating explosive 83. To wires 69 and 71 is connected electric match 85, and plug 21 is inserted into shell 77 and crimped therein.

In Figures 9, 10, and 11 is shown an apparatus suitable for carrying out the method of the invention in a modified manner. Parts of the apparatus of Figures 9, 10, and 11 which are analogous to parts of the apparatus shown in the previous figures are given corresponding primed numbers. The apparatus includes a standard 14' somewhat similar to standard 14 but in inverted position. Standard 14' is secured to support 15' by means of bolts 16' and 17'. In the upper portion 19' of standard 14' is a recess of a size to receive resilient rubber-like plug 21'. Through the bottom of portion 19' is slidably mounted sleeve holder 23' in which are fastened sleeves 45' and 47'. Sleeve holder 23' is held in portion 19' by side plates 86 and 87 (Figure 11).

Handle member 25' together with member 88, to which it is bolted by means of bolts 89 and 91, form a fork which is pivoted in standard 14' by pin 93 on which washers 95 and 97 are held by cotter pins 99 and 101. Sleeve holding element 23' contains stud portions 103 and 105 extending through slots 106 (one of which appears in Figure 10) in plates 86 and 87 respectively and through handle 25' and number 88 respectively. Hence sleeve holder 23' slides vertically in portion 19' upon operation of handle 25'. The vertical motion of sleeve holder 23' is limited by slots 106 in plates 86 and 87.

Over plug 21', at the top of the apparatus, are placed cover members 107 and 108 including handle portions 109 and 110 respectively. Cover members 107 and 108 are pivoted in standard 14' by means of two studs 111 (one of which appears in Figure 10), and held in place by means of nuts 113 and 115 respectively. Cover members 107 and 108 are also supported from upward movement by plate 117 bolted to standard 14' by bolts 119 and 121. Stud 123 extending through standard 14' and plate 117 centers the closed position of cover members 107 and 108. Spring 125 fastened to standard 14' by bolt 127 tends to hold cover members 107 and 108 in closed position so that plug 21' is covered in its recess in portion 19'. It may be seen, however, that if handle portions 109 and 110 are pressed together, cover members 107 and 108 spread apart against the action of spring 125 so that plug 21' may be inserted or removed from the apparatus. Cover members 107 and 108 are formed so that where they cover plug 21', split holes 129 and 131 are provided directly opposite sleeves 45' and 47'.

In the lower portion of the apparatus pinion 35' actuated by handle 37' drives rack bar 39' vertically. At the top of rack bar 39' is located needle holder 43' in which are fastened two needles 65' and 67'.

In the operation of the apparatus, after plug

21' has been inserted, and the device is in the position shown in Figure 10, handle 37' is turned so that needles 65' and 67' move vertically upward through sleeves 45' and 47' and into plug 21'. As needles 65' and 67' enter plug 21' needle holder 43' impinges upon sleeve holder 23' so that sleeves 45' and 47' are carried with needles 65' and 67'. The lengths of needles 65' and 67' and of sleeves 45' and 47' are of such relation that the tapered portions of the needles completely pass through the sleeves before needle holder 43' contacts sleeve holder 23'. Thus it will be seen that as needles 65' and 67' continue upward, their tapered portions first enter plug 21' and then after the needles have pierced the plug to their maximum diameter, the sleeves 45' and 47' enter and further expand holes in plug 21'. When needles 65' and 67' have reached their maximum upward movement, the sleeves will have completely passed through plug 21' and will have entered holes 129 and 131. It is to be noted that the lower portions of holes 129 and 131 are shaped to receive sleeves 45' and 47'. Needles 65' and 67' are then retracted from sleeves 45' and 47' leaving sleeves 45' and 47' extending through plug 21'. Leg wires are then inserted through holes 129 and 131 into sleeves 45' and 47' and through plug 21'. It is to be noted that holes 129 and 131 are funneled at their top portions to provide easy reception of leg wires. Handle 25' is then depressed removing sleeves 45' and 47' from plug 21' so that plug 21' shrinks about and grips the inserted leg wires. Handle members 109 and 110 are then pressed together thereby opening cover members 107 and 108. Plug 21' containing leg wires may then be lifted from the apparatus, a new plug inserted, and the operation repeated.

In Figures 12 and 13 is shown an apparatus for performing the invention in another modified manner. In these figures, parts which are analogous to portions of apparatus shown in previous figures are designated by corresponding double primed numbers.

The apparatus includes a standard 14" generally similar to standard 14 of Figure 1. Standard 14" is secured to support 15" by bolts 16" and 17". The lower portion of standard 14", designated at 19", contains a recess of a size to receive a resilient rubber like plug 21".

Through the bottom of portion 19" is slidably mounted clevis 23" which is operated by handle 25". Handle 25" is pivoted in bracket 27" on standard 14" by pin 29", and is pivoted in clevis 23" by pin 31". Clevis 23" is limited in its downward motion by pin 33".

At the top of standard 14" is rotatably mounted pinion 35" actuated by handle 37" so as to drive rack bar 39" vertically. At the base of rack 39" is affixed needle holder 43" by means of screw 42". On needle holder 43" is affixed collar 53" by means of screw 55". In needle holder 43" are affixed needles 65" and 67". It is to be noted that the tapered point portions of needles 65" and 67" do not at any point become as large in diameter as their shank portions, but that a shoulder is provided in each case at the junction of the shank portions and the tapered portions of the needles.

Clevis 23" fixedly supports two tubular sleeves 45" and 47". As clevis 23" is moved by handle 25", sleeves 45" and 47" slide respectively in tunnels 49" and 51".

Over plug 21", at the top of plug holding portion 19" of the apparatus, are placed cover mem-

bers 107" and 108" (but one of which appears in Figure 12) similar to parts 107 and 108 in Figures 9 and 10. Cover members 107" and 108" include handle portions 109" and 110" respectively. Cover members 107" and 108" are pivoted in standard 14" by means of two studs 111" (but one of which appears in Figure 12), and held in place by means of nuts 113" and 115" (but one of which appears in Figure 12). Cover members 107" and 108" are also supported from upward movement by plate 117" bolted to standard 14". Stud 123", extending through standard 14" and plate 117", centers the closed position of cover members 107" and 108". Spring 125" fastened to standard 14" by bolt 127" tends to hold cover members 107" and 108" in closed position so that plug 21" is covered in its recess in portion 19". Cover members 107" and 108" are formed so that where they cover plug 21" split holes 129" and 131" are provided directly opposite sleeves 45" and 47", and also directly opposite needles 65" and 67".

In the operation of the apparatus, after plug 21" has been inserted and the device is in the position shown in Figure 12, handle 37" is turned so that needles 65" and 67" move vertically downward through holes 129" and 131", and on through plug 21". It is to be noted that as needles 65" and 67" pass through holes 129" and 131" their shanks force cover members 107" and 108" open slightly. After needles 65" and 67" have passed through plug 21", their shoulder portions come to rest on the tops of sleeves 45" and 47". The point portions of needles 65" and 67" fit snugly inside sleeves 45" and 47", but their shank portions are of the same diameter as the outside diameter of sleeves 45" and 47".

Then handle 25" is raised pushing clevis 23" and its contained sleeves 45" and 47" upward through plug 21" pushing needles 65" and 67" ahead of them and until the shank portions of needles 65" and 67" have passed out of plug 21", and sleeves 45" and 47" have pushed all the way through plug 21" and into the lower recessed portions of holes 129" and 131". In Figure 13 is shown an enlarged view of the apparatus with sleeves 45" and 47" pushing needles 65" and 67" through plug 21". The plug is not expanded during the entry of the sleeves into it. All the expanding is done when the needles are pushed into the plug.

By turning handle 37" needles 65" and 67" are then retracted completely from sleeves 45" and 47", after which leg wires are inserted through tapered holes 129" and 131" into sleeves 45" and 47" and through the plug. Handle 25" is then depressed withdrawing sleeves 45" and 47" from plug 21" whereupon plug 21" shrinks about and grips the leg wires. Handles 109" and 110" are compressed to permit removal of plug 21", containing its leg wires, from the apparatus, and the apparatus is ready for insertion of a new plug and repetition of the operation.

One point which might be noted for all types of apparatus illustrated is that a space is provided past the plug wherever the needles or the sleeves push through the plug. Thus, as shown in Figure 3, sleeves 45 and 47 drop down far enough that needles 65 and 67 do not enter the sleeves until the needles have more than passed through plug 21. Similarly guide member 59 is shaped so that sleeves 45 and 47 pass more than all the way through plug 21 before reaching the end of their upward travel (see Figure 5).

In Figure 10, holes 129 and 131 are shaped to

receive sleeves 45' and 47' beyond the surface of plug 21'. The same shaped portion receives needles 65' and 67'.

In Figure 12, tunnels 49'' and 51'' receive needles 65'' and 67'' prior to their impingement upon sleeves 45'' and 47''. Holes 129'' and 131'' are shaped to receive sleeves 45'' and 47'' beyond the surface of plug 21''.

With these constructions, the plug is permitted space to stretch ahead of the expanding elements so that it may be fully broken through before the elements enter tight fitting portions of the apparatus. If the spaces were not provided, the expanding elements might cut rubber from the plug and small pieces of the cut rubber might jam the apparatus.

By means of the methods and apparatus just described, it is possible in a simple and convenient manner to provide a tight fitting water-proof joint between the leg wires and plug.

It will be apparent that the invention is applicable to the insertion of strand material generally through resilient substance, wherever a tight fitting engagement is desired.

Many different resilient materials may be employed in the practice of the present invention. Natural rubber, synthetic rubber as exemplified by neoprene, Buna S, Buna N or plastic material exemplified by plasticized polyvinyl chloride resin are usually found particularly applicable to the piercing procedure of the invention. However, other materials having resilience so that they will shrink and grip the inserted strand material may also be employed with advantage.

Plug materials utilized in accordance with the present invention should ordinarily be sufficiently springy and deformable that they will provide good gripping power and ease of expansion. While materials having Shore 2A durometer hardnesses as high as 90 will usually permit practical operation, it is generally preferable to employ materials having hardnesses not higher than about 75. On the other hand, it is not generally desirable that the materials be so soft that they may be readily pushed out of initiator shells or permit easy withdrawal of inserted leg wires. While materials having Shore 2A durometer hardnesses as low as about 30 often may be satisfactorily used, it is generally preferred that durometer hardnesses be at least about 60.

It will also be readily apparent that many modifications of the invention are possible. It is obvious, of course, that where, in the above description, the needles and sleeves have been moved while the plug is held stationary it is only the relative movement that is important, and the plug may be moved while the needles, for example, are held stationary.

Furthermore the methods and apparatus of the invention are also applicable to the insertion of strand material in resilient material already provided with holes. Pre-existing holes may be expanded as well as may holes produced by the needles.

What is claimed is:

1. A method of introducing a strand material through a solid resilient substance and securing the same therein, which comprises the steps of inserting a needle and a sleeve coaxially through said substance with at least the point of said needle penetrating said substance prior to penetration of said substance by said sleeve, said sleeve having an internal diameter not substantially greater than the maximum external diameter of the body of said needle, said insertion

of said needle and sleeve forming an opening through said substance of a diameter corresponding to the external diameter of said sleeve and expanding said substance; withdrawing said needle from said sleeve where said sleeve is encompassed by said substance; inserting strand material axially into said sleeve where said sleeve is encompassed by said substance; and withdrawing said sleeve from said substance while maintaining said strand material within said substance whereby said substance contracts about and grips said strand material.

2. A method of introducing a strand material through a solid resilient substance and securing the same therein as defined in claim 1, wherein said needle with said sleeve fitting concentrically around the same are simultaneously inserted through said substance from the same surface thereof.

3. A method of introducing a strand material through a solid resilient substance and securing the same therein as defined in claim 1, wherein the needle is first inserted through said substance from one surface thereof, and wherein the sleeve fitting concentrically around said needle is then passed through said substance from the same surface thereof.

4. A method of introducing a strand material through a solid resilient substance and securing the same therein as defined in claim 1, wherein the needle is first inserted through said substance from one surface thereof, and wherein the sleeve is then passed concentrically around said needle and through said substance from the surface of said substance opposite that through which said needle was first inserted.

5. A method of introducing a strand material through a solid resilient substance and securing the same therein as defined in claim 1, wherein said needle is first inserted through said substance from one surface thereof so that the point only of said needle extends beyond the surface of said substance opposite the surface of insertion of said needle, and wherein said sleeve is passed concentrically over said projecting point of said needle and then moved around said needle and through said substance from the surface of said substance opposite that through which said needle was first inserted.

6. A method of introducing a strand material through a solid resilient substance and securing the same therein as defined in claim 1, wherein said needle has a point portion of reduced diameter to provide an annular shoulder at the junction of the body portion of said needle and said point portion, wherein the said needle is first inserted through said substance from one surface thereof so that said point portion extends beyond the surface of said substance opposite the surface of insertion of said needle, and wherein said sleeve is passed over said point portion with the upper end of said sleeve engaging said annular shoulder and is forced through said substance in a direction opposite that of insertion of said needle, such movement of said sleeve simultaneously forcing said needle out of said substance and passing said sleeve through said substance.

7. An apparatus for facilitating the introduction of strand material through a solid resilient substance and securing the same therein which comprises a needle; means operatively connected to said needle for moving the same axially in either direction to cause at least the point of said needle to pass through said substance and to withdraw said needle from said substance; a sup-

port for holding said substance in position opposite the point of said needle and in alinement therewith to be pierced by at least the point of said needle as the needle is moved in one direction; a sleeve having an internal diameter not substantially greater than the maximum external diameter of the body portion of said needle; and means operatively connected to said sleeve for moving the same axially in either direction to cause said sleeve to pass through said substance and to expand said substance and to be withdrawn therefrom, the axes of said needle and sleeve being on the same straight line, said needle being moved to cause at least the point thereof to penetrate said substance prior to penetration 15 of said substance by said sleeve.

8. An apparatus for facilitating the introduction of strand material through a solid resilient substance and securing the same therein as defined in claim 7, wherein the needle and sleeve and their respective operating means for moving the same axially in both directions are located at the same side of said support so that said needle and sleeve are passed through said substance in the same direction and from the same 20 surface of said substance as said needle and sleeve are moved in one direction and are withdrawn from the said same surface of said substance as said needle and sleeve are moved in the opposite direction.

9. An apparatus for facilitating the introduction of strand material through a solid resilient substance and securing the same therein as defined in claim 7, wherein the needle and sleeve and their respective operating means for moving the same axially in both directions are located at opposite sides of said support so that the needle is passed through said substance from one 35 surface thereof as said needle is moved in one direction and is withdrawn from said substance 40 at the same surface thereof as said needle is

moved in the opposite direction, and the sleeve is passed through said substance from the surface thereof opposite said one surface after the needle has passed through said substance and as said sleeve is moved in one direction and is withdrawn from the said opposite surface of said substance as said sleeve is moved in the opposite direction.

10. An apparatus for facilitating the introduction of strand material through a solid resilient substance and securing the same therein as defined in claim 9, wherein the needle has a point portion of reduced diameter to provide an annular shoulder at the junction of said point portion and the body portion of said needle, which point portion is moved by the operating means for said needle to extend beyond the surface of said substance opposite the surface of insertion of said needle; wherein the sleeve is passed over said point portion with the upper end of the sleeve engaging said annular shoulder; and wherein the operating means for said sleeve is effective to simultaneously force said sleeve through said substance from said opposite side of said substance and to force said needle out of said substance from the surface of insertion of said needle.

DANIEL DUHURST HUYETT.
